UNITED STATES PATENT OFFICE.

HORACE W. NORWOOD, OF PHILADELPHIA, PENNSYLVANIA, ASSIGNOR TO
THE NORWOOD SPARK PREVENTIVE AND SMOKE CONSUMING COMPANY,
OF CAMDEN, NEW JERSEY.

DRAFT-REGULATOR FOR LOCOMOTIVE AND OTHER FURNACES.

SPECIFICATION forming part of Letters Patent No. 278,813, dated June 5, 1883.
Application filed December 15, 1882. (No model.)

To all whom it may concern:

Be it known that I, HORACE W. NORWOOD, a citizen of the United States, residing at Philadelphia, in the county of Philadelphia and 5 State of Pennsylvania, have invented certain new and useful Improvements in Draft-Regulators for Locomotive and other Furnaces, of which the following is a specification, reference being had therein to the accompanying drawings, wherein—

Figure 1 is a longitudinal vertical section of a locomotive-boiler, fire-box, furnace, &c., with my improvements illustrated as applied thereto; and Fig. 2 is a detail elevation.

15 My invention has relation to that class of furnaces wherein the draft is produced by injecting a blast of air or air and steam into the ash-box; and it has for its object to provide a draft which is uninfluenced by the escape of exhaust- 20 steam, and to avoid back-draft or escape of the products of combustion through the furnace-door when opened.

25 My invention accordingly consists of the novel combination and arrangement of parts, as hereinafter described, having particular reference to the provision of mechanism interposed between the injector and the furnace-door, whereby when the latter is opened the steam-supply to the injector is cut off, and back- 30 draft or the emission of the products of combustion through said opened door is avoided.

35 Referring to the accompanying drawings, A represents a locomotive-boiler; B, the stack; C, the furnace or fire-box; D, the ash-pan; c, the furnace-door; E, the exit-opening for the exhaust-ports; F, the injector, and f a pipe or connection between the boiler and injector for supplying steam to the latter.

40 To the opening E is secured a pipe, G, which runs up to near the top of the stack, as shown, and has a bore throughout its entire length of an area or diameter equal to or exceeding that of the opening E. The exhaust-steam from the cylinders therefore passes freely through said opening and pipe, and undue back-pressure in the cylinders is avoided. The exhaust escaping from the pipe G at a point near the top of the stack does not pulsate or influence the furnace-draft, consequently there is no emission 45 50 of sparks from the furnace.

The injector F may be of any suitable or desired construction; but I prefer to use that class of injectors having a rotating cut-off sleeve or nozzle, I, provided with an open end for the admission of the air designed to be 55 forced into the furnace. To said nozzle is attached a projecting finger, L, which is connected by a link, m, to a bell-crank lever, M, pivoted to the engine at m'. The end m' of lever M stands in front of the furnace-door c, 60 or its latch c', as plainly shown in Fig. 2. Hence whenever said door is opened it strikes said lever and moves it in the direction indicated by arrow x, Fig. 1. As the lever M moves the link m is depressed and the nozzle 65 or sleeve I rotated to cut off the steam to the injector, whereupon the injector stops working, and no air or steam is forced into the ash-box when the furnace-door is opened. Consequently there is no back-draft or emission of 70 sparks therethrough at such time. When the said door is closed the engineer or attendant moves the lever M to its normal position, thereby reversely rotating nozzle I to start the injector. When firing up, or when the furnace- 75 door is opened, the natural draft through the flues and smoke-stack is sufficient to get up steam or keep up its pressure. Hence it will be seen from the foregoing that the furnace-draft is maintained or produced by the injection of air or air and steam into the ash-box or furnace, that such injection is stopped whenever the furnace-doors are opened, and that the escape of the exhaust-steam does not affect the draft and the back-pressure of steam in the 80 cylinders is reduced to minimum. The injection of air into the furnace being stopped whenever the furnace-door is opened, back-draft or the emission of the products of combustion therethrough is avoided. Such result is obtained without using a blast of steam or air in the stack, as has heretofore been done. I thus effect a saving in the consumption of steam.

I have shown and described mechanism interposed between the furnace-door and the injector F; but I do not wish to be understood as confining my invention to the particular construction shown, as it may be varied to adapt my invention to different styles of locomotive-furnaces. So, too, if desired, the end of lever

M, may be connected to the furnace-door by any suitable means.

I have described my improvements as applied to locomotive-furnaces; but it is evident 5 that they may be used in connection with furnaces of all kinds. In some cases it will not be necessary to employ the pipe G, which is designed to be mainly used upon locomotives or in other places where the exhaust-steam is 10 permitted to escape into a stack. Again, I have shown and described a particular form of air-injector, because I prefer to use the same; but any other injector or forcing apparatus 15 may be substituted therefor, if desired, and when used the lever M will connect with its cut-off valve in a manner substantially as described for the nozzle I.

What I claim is—

1. In producing a draft for furnaces by injecting a blast of air or air and steam into the ash-box thereof, the method of preventing back-draft or the emission of the products of combustion through the opened furnace-doors,

which consists of automatically cutting off the supply of steam to the injector, and thereby 25 stopping its operation by the opening of the furnace-doors, substantially as set forth.

2. A furnace provided with injecting appliances for supplying air or air and steam to its ash-box, in combination with mechanism, substantially as shown and described, which is interposed between the furnace-door and the cut-off of the injecting appliances, substantially 30 as and for the purpose set forth.

3. The combination of furnace C, boiler A, 35 ash-box D, provided with injector F, connection f, door e, and mechanism interposed between said door and injector, as and for the purpose set forth.

In testimony whereof I affix my signature in 40 presence of two witnesses,

HORACE W. NORWOOD.
